UNITED STATES PATENT OFFICE.

SAMUEL GLEAVES, OF SALT LAKE CITY, UTAH.

CURTAIN-STRETCHER.

1,073,341.

Specification of Letters Patent. Patented Sept. 16, 1913.

Application filed October 11, 1912. Serial No. 725,201.

To all whom it may concern:

Be it known that I, SAMUEL GLEAVES, a citizen of the United States, residing at Salt Lake City, in the county of Salt Lake 5 and State of Utah, have invented new and useful Improvements in Curtain-Stretchers, of which the following is a specification.

This invention relates to curtain-stretchers; and has for an object to provide a 10 device of this character which will embody an extensible stretching frame having means thereon to grip the curtain positively so that upon adjustment of the frame, the curtain may be accurately and effectively 15 stretched.

A further object of the invention is to provide an extensible stretching frame which is adapted to be collapsed when not in use so that it may be stored in a very 20 small space.

Another object is to provide readily operated means by which the frame may be secured in either its collapsed or its extended, operative position, so as to effectively 25 lock the movable parts of the frame against movement in either of these positions.

A further object of the invention is the provision of corner members and telescopic 30 intermediate members connecting the angularly extended arms of the said corner members, the said intermediate portions being formed so as to move slidably within the arms of the corner members and having 35 a plurality of relatively movable resilient gripping teeth thereon which are adapted to normally spring outwardly into a position flush with the hooks provided on the arms of the corner members as the device is being 40 extended and the hooks become free from their position within the slots of the said arms.

With these and other objects in view, the invention consists of certain novel features 45 of construction, combination and arrangement of parts, as will be hereinafter described and claimed.

In the accompanying drawings:—Figure 1 is a plan view of the stretcher, showing the frame in extended position; Fig. 2 is a plan view of the same, showing the frame in collapsed position; Figs. 3 and 4 are detail sectional views through one of the side

portions of the frame; and Fig. 5 is a fragmentary perspective view of one of the intermediate sections.

The stretcher, as shown in the drawing, comprises an extensible frame, which includes the corner members 1 and the telescopic intermediate sections 2. Each corner member consists of the angularly-extending, longitudinal and lateral arms 3 and 4, respectively, which are connected at their meeting ends by means of the adjustable hinge 5, which will be more fully described hereinafter. Each arm of each corner member is constructed of rolled sheet metal, preferably which is substantially oval-shaped in cross section and provides a longitudinal slot or guideway 6 for the reception of the corresponding intermediate section 2 which is adapted to be slidably mounted therein. Each intermediate section 2 is constructed from sheet metal and is in the form of a double roll consisting of a semi-oval body portion 7 which conforms in shape to the inner periphery of the coacting arms of the adjacent corner members in which it is mounted for slidable movement, and a movable portion 8 having a plurality of swinging fingers 9 formed thereon by the provision of a plurality of longitudinally spaced incisions 10 extending from points adjacent the fold 11 in the said intermediate section to the outer edge 85 thereof, where the fingers are provided with engaging hooks 12. Each intermediate section is adapted to be secured within the working slots of the said arms of the corner members due to the provision of an 90

inward flange 13 on the upper free edge of each of said arms and which engage beneath the said fold 11 in the intermediate section, and also due to the configuration of the body portion 7 which fits snugly within 95 the receiving slots or guideways. Each intermediate section 2 is formed of resilient metal, so that the fingers 9 are adapted to swing normally into their outermost position flush with the inwardly and upwardly 100 extending curved portions 14 of the said arms of the corner members, when they are released from the guideways thereof upon extension of the frame. When the hooks are thus brought individually into their 105 outermost operative position, the hooks 12

formed thereon will be in alinement with the hooks 15 formed on the said inner portion 14 of the said arms, thus effecting their engagement with the curtain which is adapted to be associated with the said hooks 5 in order that it may be stretched upon extension of the frame. When the corresponding arms of the corner members are forced toward each other during the act of closing the frame, the fingers 9 on the intermediate sections must necessarily be sprung inwardly so that they will become engaged within the guideways of the said arms.

The intermediate sections at the ends of 15 the frame are each divided into two portions 16 and 17, which are connected at their meeting ends by means of a hinge 18, which is attached to the outside thereof to permit the said meeting ends to be swung inwardly, when it is desired to collapse the 20 frame, this motion being permitted by the hinges 5 provided for this purpose at the juncture between the side arms of the corner members.

Each hinge 5 comprises a pair of coacting 25 members, each consisting of a body portion 19, which extends longitudinally with respect to one of the arms of the corner members of which it forms a part and to the 30 upper surface of which arm it is attached by means of suitable rivets 20, and a pair of laterally extending lugs 21 and 22. The lugs 21 on each of the coacting members which constitute each hinge are pivotally 35 connected by means of a suitable bolt member 23, whereas the lugs 22 are adapted to be temporarily connected by means of a locking pin 24 which is adapted to pass through the alining openings therein when 40 the frame is in collapsed position, with the companion arms of the corner members lying in parallel planes. When the frame is in its extended position, the locking pin 24 is adapted to be inserted through an opening 45 25 provided in the body portion 19 of one of the hinge members, at one side of the pivotal connection with the lugs 21, and through the opening in the lug 22 of the coacting hinge member, thus locking the 50 frame in this position.

From the foregoing description, taken in connection with the accompanying drawings, it will be seen that I have provided an extensible frame which is adapted to be collapsed so as to occupy a small amount of space, that I have provided means for locking the movable elements of the frame in either its collapsed position or the extended position of the frame, and that I have provided a plurality of hooks on the side members of the frame, which are constituted by the corresponding arms of the corner members and the intermediate telescopic sections, which are in direct alinement with each 65 other, no matter what the adjusted position

of the said side portions of the frame may be, so that the hooks will evenly engage the cloth to be stretched within the frame.

Having thus described my invention, what I claim is:—

1. A curtain stretcher comprising a frame having corner members including longitudinal and lateral arms pivoted at their meeting ends and provided with longitudinally extending guideways, intermediate side sections telescopically mounted within the guideways of the adjacent longitudinal arms of the corner members, intermediate end sections telescopically mounted within the guideways of the lateral arms thereof, the said intermediate end sections consisting of centrally pivoted portions adapted to swing inwardly as the lateral arms of the corner members are swung inwardly in collapsed position, and a plurality of engaging hooks 85 formed on the inner edges of the said intermediate sections and the arms of the corner members.

2. A curtain stretcher comprising corner members having angularly-extending arms provided with longitudinal guideways opening at the inner edges thereof, intermediate sections slidably mounted within the guideways of the adjacent arms of the said corner members a plurality of engaging hooks 90 provided on the inner edge of each arm of the corner members, a plurality of resilient fingers formed on the said intermediate sections, an engaging hook formed on each of said fingers and adapted to aline with the 95 hooks carried by the arms of the corner members when in operative position between the adjacent ends of the said arms, the said fingers being adapted to be slidably mounted within the guideways of the said arms and to spring outwardly upon being freed therefrom to bring the hooks provided thereon into alinement with the said arm-carried hooks.

3. In a device of the class described, a pair 110 of alining arms, each arm being formed from sheet metal so as to provide a longitudinal guide slot opening through the inner side and end thereof, a plurality of engaging hooks provided upon each of said arms at one side edge of its slot, an intermediate section connecting said arms and telescopically mounted within the guide slots thereof, and a plurality of yieldable hooks provided on said intermediate section 115 for slideable movement within the arm slots, said hooks being adapted individually to spring outwardly into alinement with the arm-carried hooks upon being freed from the ends of the arm slots.

4. A device of the class described comprising a frame including corner members having pivoted arms, the meeting ends of the corresponding arms of adjacent corner members being pivotally connected, one arm 120

of each corner member being provided adjacent its point of pivotal connection with the companion members with openings angularly spaced with respect thereto, the companion arm being provided with an opening, and means adapted to be mounted movably in the latter opening for engagement within any one of said openings to secure the said

arm in different angularly adjusted positions.

In testimony whereof I affix my signature in presence of two witnesses.

SAMUEL GLEAVES.
